United States Patent Office

Des. 227,833

Patented July 24, 1973

227,833

PORTABLE STADIUM SEAT

Kenneth O. Olson, 12881 104A Avenue,
Surrey, British Columbia, Canada

Filed May 14, 1971, Ser. No. 143,737

Term of patent 14 years

Int. Cl. D6—02

U.S. Cl. D6—41

FIG. 1

FIG. 3

FIG. 1 is a perspective view of a seat in accordance with my new design as viewed from above and toward the front and left side thereof, the opposite side being identical;

FIG. 2 is a bottom plan view of the seat of FIG. 1; and

FIG. 3 is a front view of the seat of FIG. 1.

I claim:

The ornamental design for a portable stadium seat, as shown.
